(57) **CLAIM**

The ornamental design for an eye mask, as shown and described.

DESCRIPTION

FIG. 1 is a front, right and bottom perspective view of an eye mask, showing my design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a rear, left and top perspective view of the eye mask of FIG. 1 in a usable state; and,

FIG. 9 is another front elevation view of the eye mask of FIG. 8.

The broken lines in the drawings depict portions of the eye mask that form no part of the claimed design.
